FIG. 1 is a rear perspective view of an aircraft showing my new design;

FIG. 2 is a side elevation view of the aircraft shown in FIG. 1.

FIG. 3 is a rear perspective view of an aircraft showing a modification of the new design illustrated in FIG. 1.

FIG. 4 is a top elevation of the aircraft shown in FIG. 3.

FIG. 5 is a partial front elevation view of the aircraft shown in FIGS. 1-4.

The modified aircraft design shown in FIGS. 3 and 4, is substantially the same as the aircraft shown in FIGS. 1,

2 and 5, except that the single jet engine propulsion unit shown in FIG. 1 is horizontally enlarged to include two jet engines with horizontally adjacent exhausts.

I claim:

The ornamental design for an aircraft, as shown and described.
